UNITED STATES PATENT OFFICE.

WILFRED I. OHMER, OF DAYTON, OHIO.

CABINET.

SPECIFICATION forming part of Letters Patent No. 425,823, dated April 15, 1890.

Application filed June 4, 1889. Serial No. 313,099. (No model.)

To all whom it may concern:

Be it known that I, WILFRED I. OHMER, a citizen of the United States, residing at Dayton, in the county of Montgomery and State 5 of Ohio, have invented certain new and useful Improvements in Cabinets, of which the following is a specification, reference being had therein to the accompanying drawings.

This invention relates to an improvement 10 in cabinets.

The object is to produce a cabinet having a series of vertically-sliding superincumbent doors, each door carrying a lock, which may be actuated either by the hand or by springs 15 to throw the bolts into and out of contact with stops mounted within the vertical portions of a cabinet.

With these objects in view the invention consists, broadly, of a cabinet having a series 20 of vertically-sliding superincumbent doors, each door having a knob or handle suitably secured thereto, and longitudinally-sliding bolts actuated by the knob or handle for engaging suitable stops to hold the doors in a 25 raised position.

The invention consists, furthermore, in the various novel details of construction, as will be hereinafter fully described in the specification, illustrated in the drawings, and more 30 particularly pointed out in the claims.

In the accompanying drawings, forming part of this specification, and in which like letters of reference indicate corresponding parts, I have illustrated a cabinet provided 35 with a series of vertically-sliding doors, the said doors being provided with one form of lock embodying the essential features of my invention, although the same may be carried into effect in other ways without in the least 40 departing from the spirit thereof, and in these drawings—

Figure 1 is a rear elevation, in section, of a cabinet, showing a series of bolts in engagement with recesses formed in the vertical 45 portions of the cabinet and the knobs for actuating the bolts, the said knobs being shown in dotted lines. Fig. 2 is a similar view showing the bolts actuated by springs placed thereon for holding or, rather, for forcing them into contact with the stops in the vertical portions of the cabinet. Fig. 3 is a 50 similar view showing springs mounted upon

the bolts for keeping them out of contact with the stops. Fig. 4 is a vertical sectional view showing the arrangement of the doors 55 and shelves of the cabinet and also the bolts. Fig. 5 is a detail view, partly in section, showing a spiral spring mounted upon the shank of the knob for actuating the bolts. Fig. 6 is a rear elevation, taken on the line xx of 60 Fig. 5, showing the manner of arranging a spiral spring to cause it to actuate the bolts. Fig. 7 is a perspective detail view of one form of locking-bolt, and Figs. 8, 9, and 10 are similar views of other forms.

Referring to the drawings, A designates a portion of a cabinet; B and B', the side walls or vertical portions, and C the shelves, forming the compartments of the cabinet. The doors D are arranged to slide vertically in 70 grooves E, formed within the vertical portions of the cabinet, only one of the said grooves being shown in this instance. The lock for holding these doors in a raised or open position consists, essentially, of a knob 75 or handle F, carrying a shank G, which passes through the doors, and has rigidly secured at its inner end a disk H. Upon the periphery of this disk is mounted two bolts I, one end of which is provided with a longitudinal slot 80 J, through which extends a pin or screw K for holding it in place upon the disk, while the outer ends are held in position by means of guides L, so that when the knob F is turned the bolts will be caused to move in a line parallel to the lower edge of the doors. The outer ends of the bolts engage recesses M, formed in the vertical portions of the cabinet; but, if desired, a corrugated sheet of metal N, as shown in Fig. 2, or a rack-plate 90 O, as shown in Fig. 3, may be employed to accomplish the same result—viz., of holding the doors in a raised position.

In the construction just described the bolts are brought into and drawn out of contact 95 with the recesses or stops M by turning the knob or handle, which movement imparts motion to the disk and through the disk to the bolts. It may be desired, however, to so construct the bolts that they will normally be 100 in contact with the stops. In order to accomplish this result, a collar P is secured upon the outer end, and between this collar and the guide or staple L is mounted a coiled

spring Q. It will be seen that this spring will at all times keep the bolt in contact with the vertical portions of the cabinet, so that when it is desired to open the doors it will 5 only be necessary to raise them to the desired height, when the bolt will automatically engage with one of the stops and lock the door. To release the bolts, it is necessary to turn the knob F and hold it in a turned position until the door has once more resumed its 10 normal position.

In Fig. 3 I have shown the bolts so arranged that they will normally be held out of contact with the stops. This is effected by providing 15 the bolt with a collar nearest the disk upon which it is secured, and mounting the spring between the collar and the staple through which it moves. Thus it will be seen that the bolts are always out of contact with the stops. As this construction will have a 20 tendency to prevent the bolts holding the door raised by reason of the retracting action of the spring, the outer end of the bolt is formed with a toe R, which engages with the stop. Thus when the door is raised to the 25 desired height the knob is turned and the bolt allowed to engage the stop, and the weight of the door, together with the toe R, will be sufficient to overcome the retracting power of the spring; but as soon as the door is raised 30 a short distance the bolt will automatically be drawn out of contact with the stops, thus allowing the doors to be dropped to their proper places.

If desired, instead of having the spring 35 mounted upon the bolt, I may arrange a spiral spring S upon the shank of the knob, as shown in Fig. 6, and this spring may be arranged either to pull or to thrust the bolts, as desired.

In Fig. 9 I have illustrated another form of 40 lock, which consists of a single bolt T, secured to the face of the disk H. When the knob is turned, this bolt will be caused to move in a line parallel to the lower edge of the door, 45 and the outer end of the bolt will be held in position after being thrown out of engagement with the stops by means of a staple L.

In Fig. 10 I have illustrated still another 50 form of lock. In this case a weighted pawl U is actuated by means of a rod V either to engage with the recesses or stops or be thrown out of engagement therewith.

It will be very readily seen from the foregoing 55 description that, although this form of lock is

exceedingly simple of construction, it will be 55 found of the highest efficiency and durability in use and may be constructed at but a slight expense. I would have it understood, however, that I do not limit myself to the various modifications and forms shown here, but may 60 vary widely therefrom in carrying my invention into practice, so long as the essential idea of a rigid stop and bolts actuated by means of a knob be retained. I may also construct the various portions of my device—such as 65 the bolts, knob, and stops—of any desirable material—such, for example, as wood, metal, gutta-percha, &c.

I am aware that a door carrying a sliding pin for holding it in a raised position is not 70 new, and such I do not claim; but

What I do claim as my invention, and desire to secure by Letters Patent, is—

1. In a cabinet, the combination of the vertical portions thereof, having a series of stops, 75 vertically-movable doors mounted between said portions, and sliding bolts carried by the doors and engaging said stops.

2. In a cabinet, the combination of the vertical portions, a series of stops therein, vertically-movable doors mounted between said portions, a knob or handle, and bolts operated by the knob to engage the said stops.

3. In a cabinet, the combination of the vertical portions, a series of rigid stops therein, 85 sliding doors between said portions, and spring-actuated bolts for engaging the said stops.

4. In a cabinet, the combination of a series of vertically-sliding superincumbent doors, a 90 knob or handle carried by each door, a disk secured to the shank of the knob, and bolts on the disk.

5. In a cabinet, the combination of a series of vertically-sliding doors, knobs carried 95 thereby, disks on the shanks of the knobs, and spring-actuated bolts on the disks.

6. In a cabinet, the combination of a series of vertically-sliding doors, knobs carried thereby, disks on the shanks of the knobs, 100 and longitudinally-sliding bolts on the disks.

In testimony whereof I affix my signature in presence of two witnesses.

WILFRED I. OHMER.
